(57) **CLAIM**

The ornamental design for a seat, as shown and described.

DESCRIPTION

FIG. 1 is a top plan view of a seat according to one embodiment of the invention showing my new design;

FIG. 2 is a bottom plan view thereof;

FIG. 3 is a left side view thereof;

FIG. 4 is a right side view thereof;

FIG. 5 is a front view thereof;

FIG. 6 is a back view thereof;

FIG. 7 is a top plan view of a seat according to a second embodiment of the invention;

FIG. 8 is a bottom plan view thereof;

FIG. 9 is a left side view thereof;

FIG. 10 is a right side view thereof;

FIG. 11 is a front view thereof;

FIG. 12 is a back view thereof;

FIG. 13 is a top plan view of a seat according to a third embodiment of the invention;

FIG. 14 is a bottom plan view thereof;

FIG. 15 is a left side view thereof;

FIG. 16 is a right side view thereof;

FIG. 17 is a front view thereof;

FIG. 18 is a back view thereof;

FIG. 19 is a top plan view of seat according to a fourth embodiment of the invention;

FIG. 20 is a bottom plan view thereof;

FIG. 21 is a left side view thereof;

FIG. 22 is a right side view thereof;

FIG. 23 is a front view thereof;

FIG. 24 is a back view thereof;

FIG. 25 is a top plan view of a set according to a fifth embodiment of the invention;

FIG. 26 is a bottom plan view thereof;

FIG. 27 is a left side view thereof;

FIG. 28 is a right side view thereof;

FIG. 29 is a front view thereof; and,

FIG. 30 is a back view thereof.

In the drawings, the broken lines represent environmental structure forming no part of the claim.
